UNITED STATES PATENT OFFICE.

SETH WHEELER, OF ALBANY, NEW YORK.

TOILET-PAPER FIXTURE.

SPECIFICATION forming part of Letters Patent No. 447,419, dated March 3, 1891.

Application filed July 11, 1890. Serial No. 358,448. (No model.)

To all whom it may concern:

Be it known that I, SETH WHEELER, of the city and county of Albany, and State of New York, have invented certain new and useful 5 Improvements in Paper - Roll Holders, of which the following is a specification, reference being had to the accompanying drawings, forming part thereof.

This invention relates to improved means 10 for applying friction to a roll of paper at its center.

It consists in applying friction to the inner periphery of the roll of paper held in position between the arms of the roll-holder by a fixed 15 roller, whereby the sheets of paper forming the roll will be removed one at a time and without any unnecessary unwinding of the roll of paper, and means for preventing the roll from turning in but one direction.

20 In the drawings, Figure 1 is a front view of a fixture to which my invention is applied, a portion of the roll of paper being removed. Fig. 2 is a vertical cross-section taken through the line X X of Fig. 1. Fig. 3 is a view of the 25 roller, showing one form of the friction attachment.

a is a roller held rigidly between the arms b b of a roll holder or fixture. In the present instance these arms swing. They can, however, be stationary—namely, rigidly attached, one at each side, to an extension downwardly of the back c. The operation of the roll of paper upon the roller would be the same in either case. The roller a being in either case 35 stationary in the fixture, the roll of paper d, moving upon such roller, has friction applied to its inner periphery. I attach a spring e to the periphery of the roller by means of screws f f, &c. The outer and free end of this spring 40 e presses outwardly against the inner periphery of the roll of paper d. The paper moving in the direction of the arrow shown in Fig. 2 by a pull upon the free end of the web

will be retarded in its forward movement, and on the strain increasing a sheet of paper will 45 be severed on its line of weakness. As soon as the severance is effected this intermediate friction between the roller and roll of paper will stop the movement of the latter, and thus any unnecessary unwinding of the roll is prevented. In this way but one sheet at a time 50 is withdrawn. This friction between the stationary roller a and the roll of paper d (shown in the drawings) has also the merit of not permitting the roll to be turned in the opposite 55 direction to that shown by the arrow in Fig. 2, because the free end of the spring e would then penetrate the roll of paper and arrest its motion.

In my improved construction of fixture 60 shown in the drawings the roller a is inserted and held therein as follows: b b are two spring-arms having at their outer ends, facing inwardly, two cup-shaped sockets h h. In each of these sockets is a pin i i. In the ends of 65 the roller a, placed centrally, are two slots j j, which are large enough for the pins i i to enter. The spring-arms are spread apart sufficiently to permit the ends of the roller a, after the roll of paper has been placed thereon, being inserted in these cup-shaped sockets h h, the pins i i thereby engaging with the slots j j in the ends of the roller, and the roller is consequently held rigidly within said arms. 70

I claim—

In a paper-holder, the combination of a stationary roller with a roll of paper and an intermediate spring e for producing friction between the periphery of the roller and the inner periphery of the roll of paper and to prevent the roll of paper from turning in but one direction, substantially as described. 80

SETH WHEELER.
